UNITED STATES PATENT OFFICE.

LARS A. ERICKSON, OF WEST PULLMAN, ILLINOIS.

DESIGN FOR A HANGER FOR WAGON-WHEELS.

SPECIFICATION forming part of Design No. 34,138, dated February 26, 1901.

Application filed January 30, 1901. Serial No. 45,393. Term of patent 7 years.

To all whom it may concern:

Be it known that I, LARS A. ERICKSON, a citizen of the United States, residing at West Pullman, in the county of Cook and State of Illinois, have invented and produced a new and original Design for Hangers for Wagon-Wheels, of which the following is a specification, reference being had to the accompanying drawings, forming part thereof.

10 Figure 1 is a bottom plan view of a hanger, showing my new design. Fig. 2 is a side view thereof, and Fig. 3 is an end view.

As shown in the drawings, the leading or material feature of my design consists of a 15 cross-piece A, having a smooth upper surface and a rib a on its lower surface. At each end of the cross-piece A is a portion B, which is formed with a longitudinal opening b, and has its ends rounded and provided with openings 20 b', circular in shape. Extending downwardly from each of the portions B are two portions

C and C', which are substantially triangular in form and have substantially triangular openings c. Each of the portions C and C' is formed in its lower end with an opening c, 25 circular in shape. Extending from the lower ends of the parts C' and united to the rib a of the cross-piece A is an arched rib D, through the middle of which is an opening d, circular in shape. 30

Having described my invention, what I claim as new, and desire to secure by Letters Patent, is—

The design for a hanger for wagon-wheels, substantially as herein shown and described. 35

In testimony whereof I have signed my name to this specification in the presence of two subscribing witnesses.

LARS A. ERICKSON.
